US00D886153S

(12) **United States Design Patent** (10) **Patent No.:** **US D886,153 S**
(45) **Date of Patent:** **** Jun. 2, 2020**

- (54) **DISPLAY SCREEN OR PORTION THEREOF WITH GRAPHICAL USER INTERFACE**
- (71) Applicant: **Apple Inc.**, Cupertino, CA (US)
- (72) Inventors: **Jonathan P. Ive**, San Francisco, CA (US); **Brian Andrew Schmitt**, San Francisco, CA (US); **Wan Si Wan**, Sunnyvale, CA (US); **Christopher Wilson**, San Francisco, CA (US)
- (73) Assignee: **Apple Inc.**, Cupertino, CA (US)
- (**) Term: **15 Years**
- (21) Appl. No.: **29/720,406**
- (22) Filed: **Jan. 13, 2020**

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
